GARDNER B. GRAY, OF PITTSBURGH, PENNSYLVANIA.

POWER-ACTUATED SWITCH-CONTROL SYSTEM.

1,198,021.

Specification of Letters Patent. Patented Sept. 12, 1916.

Application filed April 18, 1914, Serial No. 832,722. Renewed February 12, 1916. Serial No. 78,068.

To all whom it may concern:

Be it known that I, GARDNER B. GRAY, a citizen of the United States, and a resident of Pittsburgh, in the county of Allegheny and State of Pennsylvania, have invented 5 certain new and useful Improvements in Power-Actuated Switch-Control Systems of which the following is a specification.

The present invention relates to power actuated switches used at railroad terminals or the like, the nature of the power used being immaterial, and has for its main object increased safety and certainty of operation. Heretofore in systems of this character 15 safety devices have been utilized on the principle of preventing power from reaching the switch machine, for in such systems once power is applied to the switch machine the latter will go through its cycle of functions 20 to operate the switch. Experience has demonstrated the impossibility of at all times preventing the application of power to the switch machine. Furthermore, if the lock-rod is unlocked and the switch moved manually, as by a malicious person, safety means to counteract such movement should be provided.

Accordingly the main feature of this invention resides in making the switch machine self protecting, so that, even if power 30 improperly reaches it, such power will tend to lock the switch machine and switch in the position which they occupy. And should it be attempted to unlock the lock-rod or to 35 move the throw-rod and thereby the switch, power will immediately be applied to restore the parts to their original position.

The complete actuation of the switch requires substantially three distinct steps, 40 namely, unlocking, moving and relocking the switch. At the present time these steps are performed in one continuous operation. In the herein disclosed preferred embodiment of the invention this operation is performed 45 by stages instead of in one continuous operation, and preferably, as in the precise disclosure here made, step by step. The advantage of this is that means are provided whereby the operating means are prevented 50 from effecting any stage of operation unless the previous stage has been completed.

Another feature of the invention resides in a construction whereby power is normally cut off from the operating means for the switch, 55 and in an auxiliary locking means for the switch through which, and through which

only, power can be supplied whether properly or falsely, to the operating means, together with a controller, actuated by the movement of the operating means, for cutting off power between the means for supplying power to the operating means and the latter. The effect of this is that if the power is falsely supplied, the movement of the controller of the operating means will 60 not cut off power and consequently the auxiliary locking means will continue to hold the switch in its locked position.

Other features of construction, combination of parts and arrangement of elements 70 will appear as the specification proceeds.

In the accompanying drawings the invention is embodied in a concrete and preferred form but changes may be made within the scope of the appended claims, without departing from the legitimate and intended 75 scope of the invention.

In the said drawings: Figure 1 is a diagrammatic view of a preferred form of a power actuated system of switch and signal control embodying the invention. Fig. 2 is a plan view of the switch and switch machine. Fig. 3 is a longitudinal sectional view of the differential transmission mechanism. Fig. 4 is a perspective view of interlocking means which may be used between the two levers of the controlling means in the tower machine. Fig. 5 is a detail view of the crank 7 and throw-rod 3. Fig. 6 is a detail view of the lock-rod 2 and member 56. Fig. 7 is a detail view of one of the levers 21-22. Fig. 8 is a development of the cam 11 which actuates the controller 10.

Similar characters of reference indicate corresponding parts in the different views.

1 indicates the switch or switch points. 2 is the lock-rod and 3 the throw-rod, both of said rods being suitably connected to said switch in a well-known manner.

4 is the motor, 5 the differential transmission mechanism, 6 the driven shaft having the crank 7 engaging in a suitable notch 8 in the throw-rod 3.

10 is a controller actuated by means of the cam 11 on the shaft 6 so as to move in accordance with the movement imparted to the throw-rod.

12 is the controller which is actuated by the locking member 13 of the lock-rod.

14 is the actuating means for the locking member, here shown as a double solenoid.

15 is the auxiliary locking device for the

locking member of the lock-rod and 16 is the auxiliary locking device for the throw-rod.

17 is a diagrammatic representation of the usual detector bar which may be connected up to the locking member 13 of the switch machine.

18 is a signal post along the line of way, 18^a and 18^b the semaphores thereof, and 19^a and 19^b are the motors therefor.

10 21 is a lock lever. 22 is a switch lever, and 20^a is a signal lever controlling the semaphores.

23 is a controlling means actuated by the lock lever, 24 is a controlling means actuated 15 by the switch lever and 24^a is a controlling means actuated by the signal lever.

25 is the source of power for operating the switch and signals.

The movement of the contact 26 of the controlling means 23 from engagement with the springs 27 and 28 into engagement with the springs 29 and 30, establishes a circuit as follows: from battery 25, to bus bar 31, through conductor 32, conductor 33, spring 25, contact 26, spring 30, conductor 34, to

spring 35, contact 36, spring 37, conductor 38, to auxiliary lock solenoid 16 and common return 39, to battery 25. This energizes the lock solenoid 16, drawing the core 40 there-

of upward and causes the locking dog 41, pivoted at 42, to move downward at its outer end so as to engage the locking collar 43 on the driven shaft 6, and at the same time moves the contact 44 from engagement with

the springs 45 and 46 into engagement with the springs 47 and 48 and the contact 49 into engagement with the springs 50 and 51. This establishes a circuit as follows: from conductor 38, conductor 52, spring 48, contact

40, 44, spring 47, conductor 53, to the coil 54 of lock solenoid 14, conductor 55, spring 51, contact 49, spring 50 and common return 39. The energization of the coil 54 of the lock

45 solenoid 14 moves the locking member 13 to the left (Figs. 1 and 2), thereby drawing the projection 56 out of notch 600 in the lock-rod 2, thus releasing the same or unlocking the switch. At the same time the contact 36 is moved out of engagement with

50 the springs 35 and 37 and the contact 57 connects up the springs 58 and 59. This cuts off power between the controlling means 23 and the actuating means or lock solenoid 14, and auxiliary locking device or sole-

55 noid 16, thereby deenergizing 54 and 16 and causing the core 40 to move downward and the locking dog 41 to free itself from engagement with the locking collar 43. It will further be noted that when the auxiliary locking device 16 was energized it

60 ruptured the signal circuit 60 by moving the contact 44 out of engagement with the springs 45 and 46 and that the locking member 13 by moving to the left also ruptured the signal circuit 60 by moving the contact

61 out of engagement with the springs 62 and 63. While the signal circuit 60 therefore is restored by the deenergization of the auxiliary locking device 16 at that point, it remains ruptured at the point where it 70 passes through the controller of the locking member 13.

Let us assume that current has been improperly supplied by a cross or otherwise on line conductor 34. Then current would flow 75 along this conductor from the point of cross through spring 35, contact 36, spring 37, conductor 38, coil of auxiliary locking device 16 and to common. After 16 is energized and shaft 6 held against rotation current would flow to the coil 54 of solenoid 14, thus causing the locking member 13 to move to the left (Figs. 1 and 2). This would immediately establish a circuit through the coil 105 as contact 57 will at once be moved to 80 the left (Fig. 1) to bridge the springs 58 and 59. This would immediately hold the locking member 13 in a mid position in which position the switch is still locked, while at the same time shaft 6 is also held 85 locked and these conditions will continue so long as current flows. Again assume that current has been improperly supplied along the conductor 38 by a cross or otherwise, then the auxiliary locking device 16 will 90 first lock the shaft 6 and then energize coil 54 so as to move the locking member 13 to the left (Fig. 1), and, as before, it will be held in mid position. Furthermore the signal circuit 60 will also remain ruptured in 95 both of these cases at the point where it passes through the controller of the auxiliary locking device 16. The first stage of the cycle of operations of the switch now having been accomplished, the operator 100 moves the lever 22 to the left, thereby moving the contact 64 out of engagement with the springs 65 and 66 of the controlling means 24 and placing contact 64 between the springs 67 and 68. The movement of 105 the contact 64 into the position designated will establish a circuit as follows: from battery 25, bus bar 31, conductor 69, conductor 70, spring 67, contact 64, spring 68, conductor 71, spring 72, contact 73, spring 74 of the 110 controller 10, conductor 75, reverse magnet 76, conductor 77, to auxiliary locking device 15, and thence to common return 39 and battery 25. The reverse magnet 76 forms a 115 part of the selective means between the motor and the driven shaft 6 and when energized tightens the band 78 on the drum 79, which thereby selectively connects the motor 4 to drive the shaft 6 in a certain direction. The energization of the auxiliary locking 120 device 15 causes the core 80 thereof to be moved upward, thereby moving the contact 81 away from the springs 82 and 83 so as to break the continuity of the signal circuit 60 at that point and move said contact into en- 125 130

engagement with the springs 84 and 85, and at the same time causes the contact 86 to bridge the space between the springs 87 and 88. This establishes a circuit as follows: from 5 the conductor 77, to conductor 89, spring 84, contact 81, spring 85, conductor 90, motor 4, motor field 91, conductor 92, spring 88, contact 86, spring 87 and common return 39, back to battery 25. This causes current to 10 flow through the motor 4 which by its rotation and by means of the reverse magnet 76 and the differential transmission mechanism, causes the shaft 6 to be driven in a certain direction whereby the crank 7 engaging with 15 the notch 8 of the throw-rod 3 moves the latter and throws the switch to reverse position. The rotation of the shaft 6 causes the cam 11 to actuate the controller 10, whereby the contact 73 is moved to the right 20 (Fig. 1) and is out of engagement with the springs 72 and 74, thereby cutting off all power between the source 25 and the controlling means 24 and reverse magnet 76 and auxiliary locking device 15, whereby 76 and 25 15 are both deenergized. This releases the band 78 from its clutched position and destroys the circuit through the motor, restores the signal circuit 60 at the point where it passes through the auxiliary locking device 30 15 and causes the branch 60^a of the signal circuit 60 to be ruptured by the movement of the contact 93 away from the springs 94 and 95 in the controller 10, and closes the branch 60^b of the signal circuit 60 where it 35 passes through the controller 10 by causing the contact 93 to engage the springs 96 and 97. The movement of the switch further places the normal magnet 108 ready to be energized by moving the contact 99 into engagement with the springs 100 and 101 in the controller 10. It will be observed that the signal circuit 60 is still ruptured where it passes through the controller of the locking member 13. 40

45 It will be observed that had current been supplied to the motor 4 before the locking dog 56 had released the lock-rod 2, the energization of the auxiliary locking device 15 would have caused the lower end of the core 50 80 to have engaged in the notch 102 of the locking member 13 so that, while the motor 4 would have rotated, the lock-rod and the locking member therefor would both have been locked and the signal circuit would 55 have been ruptured at the point where it passes through the controller of the auxiliary locking device 15.

The second stage of operation of the switch having been completed the operator 60 now moves the lever 21 back to the right, thereby causing the contact 26 to bridge the space between the springs 27 and 28. This establishes the following circuit: from the battery 25 to bus bar 31, conductor 32, spring 65 27, contact 26, spring 28, conductor 103, spring 58, contact 57, spring 59, conductor 104, to coil 105 of locking solenoid 14, and thence to common return 39 and back to battery 25. This energizes the said coil 105, drawing the locking member 13 to the right 70 (Fig. 1), thereby causing the dog 56 to engage in notch 601 of the lock-rod 2, thus locking the switch. At the same time the contact 61 bridges the space between the springs 62 and 63 and completes the signal 75 circuit 60 at that point, thereby permitting the clearing of signal 18^b for the passage of traffic by moving the lever 20^a to cause the contact 20^b to engage springs 20^c and 20^d in controller 24^a thereby supplying power to 80 motor 19^b. This completes the third stage of operations and also one complete cycle of movement of the switch.

When it is desired to move the switch from the reverse position to the normal 85 position the lever 21 is moved to the left and the first stage of operations, as previously described, repeated. The operator now moves the switch lever 22 to the right and breaks the contact 64 between the 90 springs 67 and 68, and causes it to bridge springs 65 and 66, thereby establishing the following circuit: from battery 25 to bus bar 31, conductor 69, spring 65, contact 64, spring 66, conductor 106, spring 101, contact 99 spring 100, conductor 107, to normal magnet 108, conductor 77, to auxiliary locking device 15, and thence to common return 95 39, back to battery 25. This energizes the said normal magnet 108, causing the band 100 109 to be tightened on the pulley 110, and further causes the energization of the auxiliary locking device 15 and an upward movement of the core 80. This establishes the following circuit: from conductor 77, to conductor 89, spring 84, contact 81, spring 85, conductor 90, to motor 4, motor field 91, conductor 92 spring 88, contact 86, spring 87, and common return 39. This rotates the motor 4 which by means of the differential 105 transmission mechanism 5 and the normal magnet 108 causes the driven shaft 6 to rotate in a direction opposite to that from which it rotated on the reverse movement, thereby causing the crank 7 to engage in the notch 8 of the throw-rod 3 and move the switch back to normal position. The movement of the shaft 6 further causes the cam 11 to move the controller 10 to the left 110 (Fig. 1), thereby moving the contact 99 out 115 of engagement with the springs 100 and 101 and thus cutting off power between the controlling means 24 and the normal magnet 108 and the auxiliary locking device 15, as 120 well as the motor 4. The movement of the controller 10 further moves the contact 93 from engagement between the springs 96 and 97 into engagement with the springs 94 and 95, thus breaking signal circuit 60^b and closing signal circuit 60^a at that point. 130

This completes the second stage of operations of the normal movement of the switch. The lock lever 21 is now moved to the right to lock the switch in the same manner as described in connection with the reverse movement of the switch so that the switch is now locked and the third stage of operation completed, and the complete cycle of movement of the switch to normal is finished. The signal 18^a may now be cleared by supplying power to the motor 19^a by means of the lever 20^a.

It is obvious that the same safe-guards that were pointed out in connection with the unlocking, moving and locking of the switch on the reverse movement obtain on the normal movement.

When the switch is in either of its positions and locked up, it is cut off from all power and is, as described, capable of nullifying the effect of any improperly supplied current, in that the application of such current to the switch machine only serves to lock it additionally. Should it now be attempted to forcibly move the locking member 13, by a malicious person or otherwise, so as to cause the lock-rod 2 to be unlocked, it is evident that such movement will cause the contact member 57 to engage between the springs 58 and 59. This will immediately establish a circuit from battery 25 to bus bar 31, conductor 32, spring 27, contact 26, spring 28, conductor 103, spring 58, contact 57, spring 59, conductor 104, coil 105 of locking solenoid 14, common return 39, back to battery 25. The effect of this circuit, as previously pointed out, will be to cause the locking member 13 to be moved to the right (Figs. 1 and 2), thereby locking the lock-rod 2 again. Thus the very act of unlocking the switch supplies power to the locks, whereby it will lock itself again automatically. Again, should it be attempted to move the throw-rod 3, say after sawing through or otherwise breaking the lock-rod 2, then the very act of moving the said throw-rod will cause a movement of the controller 10. If the switch were in the normal position and is moved to the reverse position, the contact 99 will bridge the springs 100 and 101 and a circuit will be established from battery 25, bus bar 31, conductor 69, spring 65, contact 64, spring 66, conductor 106, spring 101, contact 99, spring 100, conductor 107, normal magnet 108, conductor 77, auxiliary locking device 15 to common return 39, back to battery 25. This circuit would in turn, by reason of the energization of the auxiliary locking device 15, cause a circuit to be established through the motor as follows: conductor 77, conductor 89, spring 84, contact 81, spring 85, conductor 90, motor 4, motor field 91, conductor 92, spring 88, contact 86, spring 87 and common return 39. The effect of this

circuit would be to cause a movement of the switch back to its normal position. Similarly if the switch is in the reverse position and it should be attempted to move it to the normal position by a physical displacement of the throw-rod 3, a circuit would be established as follows: from battery 25, to bus bar 31, conductor 69, conductor 70, spring 67, contact 64, spring 68, conductor 71, spring 72, contact 73, spring 74, conductor 75, reverse magnet 76, conductor 77, auxiliary locking device 15, to common return 39, back to battery 25. The energization of the auxiliary locking device 15 would, as before, establish the circuit through the motor 4 and thus cause the switch to be moved to reverse position. It will further be noted that, if the switch-rod 3 or the locking member 13 should be maliciously moved in the manner above described, the signal circuit 60 through these various controllers would be ruptured and prevent the giving of a signal for the passage of traffic. A still further advantage of the system is that if the operator after throwing the lock lever 21, say to unlock the switch, should change his mind, the reversal of the said lever 21 would immediately restore the switch to its locked position without affecting the switch moving means in any way. This advantage is obtained as follows: The mechanical connection between the cam 11 on shaft 6 and controller 10 and between core 13 and controller 12 are so arranged that while 11 or 13 makes a complete movement in either direction, the controllers 10 and 12 are given two intermittent motions. In the case of the controller 12 and core 13 this may be effected as follows: Connected to the controller 12 is a link 13^a pivoted at 13^b and provided with a member 13^c rigidly connected to said link and having the end stops 13^d and the intermediate stops 13^e. Carried by the core 13 is a projection 13^f. When the parts are in the position shown in Fig. 2 and the coil 54 is energized the projection 13^f will engage one of the intermediate stops 13^e and will thereby move the link 13^a until it occupies a central position permitting the projection 13^f to continue its movement without imparting further motion to the link 13^a. The effect of this is to move the controller 12 sufficiently to cause the contact 57 to engage the springs 58 and 59 without causing the contact 36 to pass out of contact with the springs 35 and 37, so that the controller in this position connects up two paths for the power. This movement also breaks the engagement of contact 61 with springs 62 and 63, thus rupturing the signal circuit. The continued movement of the projection 13^f will then eventually bring it against the left-hand stop 13^d causing the link 13^a to tilt to the left imparting a sec-

ond movement to controller 12 which brings the contact 36 out of engagement with the springs 35 and 37. On the return movement the same intermittent action occurs. 5 This permits of a longer interval of time in which to effect the reversal of the controlling means 23 since the controller 12 has established two paths or connections to the solenoid 14, so that in case the switchman 10 has made an error he may correct it. Thus a connection is immediately established permitting the return movement of the core 13, so that the locking member will follow the movement of its lever 21. The return circuit which could be established in this manner has previously been described.

In the case of the controller 10 and cam 11 the action is as follows: The crank 7 moves about 15° before it starts to move 20 throw-rod 3 by engaging in the open slot 8 thereof. During this 15° movement the roller 11^c of the pivoted connection 11^a traverses the part 11^a of the cam 11 thereby bringing contact 99 between springs 100 and 25 101 without however causing contact 73 to pass out of engagement between springs 72 and 74. Contact 93 also passes from engagement with springs 94 and 95 but not into engagement with springs 96 and 97. During 30 the further revolution of the crank 7 and while it is moving the throw-rod 3 the roller 11^c traverses the straight portion of the cam 11 and the controller 10 is not moved. When the crank 7 has finished moving 35 throw-rod 3 it continues to revolve about 15° further during which time the roller 11^c passes through the portion 11^b of the cam 11 thereby imparting an additional movement to the controller 10 which causes the 40 contact 73 to disengage springs 72 and 74 and the contact 93 to engage springs 96 and 97. The movement in the reverse direction is of the same character. Thus it will be seen in this case also a sufficient interval of 45 time is provided in which the reversal of the controlling means 24 will cause a reversal of movement of the shaft 6 by the establishment of circuits previously described. It will further be understood that, should the 50 collar 43 on shaft 6 be improperly positioned when the auxiliary locking device 16 is energized, the dog 41 cannot descend and consequently the circuit through the coil 54 cannot be established. Likewise should the core 55 13 be improperly positioned when the auxiliary locking device 15 is energized the lower end of core 80 would not clear the said core 13 and no circuit would be established through the motor. But in both instances 60 the signal circuit 60 would be ruptured. Thus the auxiliary locking devices test the position of the parts of the switch to ascertain whether or not they are correctly positioned.

65 It will of course be understood that the

parts comprising the switch machine are properly inclosed or housed; further that the controlling means 23, 24, 24^a and levers 21, 22, 20^a and interlocking therefor are housed in a suitable tower machine, and 70 finally that the conductors leading from the tower machine to the switch machine are properly trunked or inclosed to protect the same from injury and exposure.

The differential transmission mechanism 75 5 is preferably constructed as follows: 111 is the motor shaft disconnected from the driven shaft 6 but in alignment therewith. Mounted on the motor shaft 111 and keyed thereto is a gear 393. Keyed on the driven 80 shaft 6 is the internal gear 303. Mounted loosely on the hub of gear 303 and on the motor shaft 111 are two members 398 connected by pins 399 so as to cause them to move in unison. These pins are 180° apart. 85 Mounted loosely on the pins 399 are sleeves 397. Mounted fast on each of the sleeves 397 are three pinions 394, 395 and 396. The pinion 394 receives motion from the gear 393 and meshes with the internal gear 303. 90 The pinion 395 is of slightly greater diameter than the gear 394, follows the motion of the sleeve 397 and meshes with the internal gear 308 of the pulley 79. The pinion 396 is of slightly less diameter than the pinion 394, follows the rotation of the sleeve 95 397 and meshes with the internal gear 302 of the pulley 110. The solenoids 76 and 108 are each provided with a core 112 connected by means of a link 200 to two levers forming a bell crank 113, which levers are pivotally supported on the center 201, and one of which levers is longer than the other one, as shown. The bands 78 and 109 pass around the drums 79 and 110, and the free 100 ends of said bands are connected to the levers 113. If the motor shaft 111 is now rotated and the shaft 6 held against rotation, the gear 393, meshing with the pinions 394 will cause them, and the sleeves 397, to 105 rotate. Pulleys 79 and 110 being free to revolve, and the gear 303 being held against revolving movement, the pinions 394 will revolve by traveling on the internal gear 303 carrying the sleeves 397 and the members 398 with them. The rotation and revolution of the sleeve 397 and pinions 395 and 396 will cause the latter to travel on the internal gears 308 and 302 and will also cause 110 said gears 308 and 302, and with them the 115 pulleys 79 and 110, to revolve one pulley in one direction and the other pulley in the other direction, due to the difference in diameter of the pinions 394, 395 and 396. If now the shaft 6 is free to rotate and the 120 magnet 76 is energized, the core 112 thereof will be withdrawn thereby turning the levers 113 around the center 201 and tightening the band 78, so as to hold the pulley 79 125 movable. The rotation of the sleeves 397 130

and pinion 395 will cause the latter to travel on the rigidly held gear 308, causing the sleeves 397, pins 399 and members 398 to revolve. The pinion 394 will attempt to travel on gear 303, but since the peripheral speed of the pinion 394 is less than that of pinion 395, said pinion 394 will drag the gear 303 with it and cause it to revolve and with it the shaft 6. The pulley 110 being movable will also revolve by the action on the pinion 396 on the internal gear 302. Assume now that the shaft 6 is still free to rotate, that the magnet 76 is deenergized, the band 78 released, and the pulley 79 free to revolve. If the magnet 108 is now energized, the core 112 thereof will be withdrawn thereby turning the levers 113 around the center 201 and tightening the band 109 to hold the pulley 110 immovable. The rotation of the sleeves 397 and pinion 396 will cause the latter to travel on the rigidly held gear 302, causing the sleeves 397, pins 399 and members 398 to revolve. The pinion 394 will attempt to travel on gear 303, but since the peripheral speed of the pinion 394 is greater than that of pinion 396, said pinion 394 will lag behind and will actually push back the gear 303, and cause it to revolve in the opposite direction and with it the shaft 6. In order to return the cores 112 to their original uppermost position, when the magnets 76 and 108 are deenergized, springs 114 are utilized.

The controlling means situated in the tower machine may be of any suitable form, but preferably they are constructed as follows: Since the levers 21, 22 and 20^a are, in the present instance, of the same construction, only one will be described. The lever 21 is pivotally supported at 550 and carries a latch 551 by means of which the latch die 552 can be raised or lowered. 553 is a stationary segment drawn on an arc of a circle whose center is the pivot 550. 554 is a movable segment having a segmental slot 555 drawn on an arc of a circle whose center is the pivot 550, and pivoted centrally at 556 directly above the pivot 550. One end of 554 is pivotally connected to the controlling rod 557 while the other end is connected to the shaft 125 by means of the bifurcated arm 127 and link 126 in such a manner that the rocking movement of 554 is imparted to the shaft 125. The latch die 552 is slidably movable in the slot 555 and on the stationary segment 553. It will be evident that such movement will not cause the movable segment 554 to rock. At each end of the stationary segment 553 is a notch 558 into and out of which the latch die 552 can be moved by manipulation of the latch 551, thereby causing the movable segment 554 to rock and impart movement to the controlling rod 557 and to the shaft 125. The shaft 125 carries

with a rack 506 attached to the slidable bar 500. This bar 500 slides transversely in a notch in the frame bar 507. To the bar 500 is riveted the locking dog 501, the face of which is beveled. The frame bar 507 is provided longitudinally with guiding lugs which support a cross locking bar 502, the ends of which are beveled. Mounted in the frame bar 507 adjacent to the bar 500 is another slidable bar 504 carrying riveted to it a locking dog 503 having a beveled face. The beveled faces of the locking dogs 501 and 503 coöperate with the beveled ends of the cross locking bar 502. The bar 504 is connected to the shaft 125 of the switch lever 22 by a rack and segmental gear in the same way as the shaft 125 of lever 21 is connected to the bar 500.

In the operation, the rocking of the shaft 125 by the movement of the latch 551 of the lock lever 21, as described, moves the bar 500 (to the right in the figure) and the locking dog 501 shifts the cross locking dog 502 to the right and engages it in front of the locking dog 503 and holds the bar 504 against movement. This prevents the movement of the shaft 125 of lever 22 and restrains the latter against movement, so as to maintain the lock lever 21 in normal position. The movement of the latch 551 when lock lever 21 is in normal position raises the latch die 552 out of the notch 558 thereby rocking the segment 554 and moving the controlling rod 557 sufficiently to bring the contact member 26 out of engagement with the springs 27 and 28 but not sufficiently to bring the contact member 26 into engagement with the springs 29 and 30. The rocking of the segment 554 also moves the interlocking between the levers 21 and 22 by turning the shaft 125 as described but not far enough to cause dog 501 to release cross locking bar 502; therefore switch lever 22 cannot yet be moved. The lever 21 is now moved, the latch die 552 traveling through segment 554 without rocking the same and over the surface of the segment 553; the controlling rod 557 remaining in its midway position above described so that the circuits are fully open. When the latch die 552 reaches the other end of the segment 553 the latch 551 is again manipulated, thereby lowering the latch die 552 into the other notch 558, rocking the segment 554, causing the contact member 26 to engage springs 29 and 30 and releasing the interlocking by turning the shaft 125 into the position shown in Fig. 4, that is lock lever is now reversed and dog 501 releases cross locking bar 502 and switch lever 22 can now be moved.

What is claimed, is:

1. A power actuated system of switch control comprising: a switch, operating means for unlocking, moving and locking the switch, controlling means for supplying

power to said operating means, and means for locking the switch when the operating means are improperly supplied with power.

2. A power actuated system of switch control comprising: a switch, power actuated operating means for unlocking, moving and locking the switch normally cut off from power, power actuated auxiliary means for locking the switch when power is applied to the operating means, controlling means for supplying power to the operating and auxiliary means, and means actuated by the operating means for cutting off power from the operating and auxiliary means.

3. A power actuated system of switch control comprising: a switch, operating means for unlocking, moving and locking the switch, controlling means for supplying power to the operating means, and auxiliary means for additionally locking the switch if power is supplied to move the switch before unlocking the same.

4. A power actuated system of switch control comprising: a switch, operating means for unlocking, moving and locking the switch, controlling means for supplying power to the operating means, and auxiliary means, actuated by the power from the controlling means, for locking the switch against movement during the unlocking operation.

5. A power actuated system of switch control comprising: a switch, operating means for unlocking, moving and locking the switch, controlling means for supplying power to the operating means, auxiliary means, actuated by the power from the controlling means, for locking the switch against movement during the unlocking operation, and means actuated by the operating means for cutting off power from the operating and auxiliary means when the unlocking movement of the operating means has been effected.

6. In a system of power actuated switch control, a switch, a lock-rod connected thereto, a locking member for the lock-rod, actuating means for moving the locking member and switch, controlling means for supplying power to said actuating means, and auxiliary means for locking the locking member when power is supplied to move the switch before releasing the locking member from the lock-rod.

7. In a system of power actuated switch control, a switch, a throw-rod connected thereto, actuating means for said throw-rod normally inoperative, a normally open circuit for said actuating means, means for closing the circuit through the actuating means to cause movement of the throw-rod, another circuit normally open, and a circuit controller connected to the throw-rod, whereby when the throw rod is physically

displaced other than by the actuating means the latter circuit will be closed and power applied to the actuating means to restore the throw-rod to its original position.

8. A power actuated system of switch control comprising: a switch, operating means for unlocking, moving and locking the switch, two auxiliary locking devices which when sequentially actuated by power admit power a plurality of times to the operating means to effect the recited cycle of operations thereof, and means for supplying power sequentially to the auxiliary devices.

9. A power actuated system of switch control comprising: a switch, operating means for unlocking, moving and locking the switch, a power actuated auxiliary device which supplies power to the operating means to unlock the switch and locks it at another point, a power actuated auxiliary device which supplies power to the operating means to move the switch and controlled by the operating means to additionally lock the switch unless it has been previously unlocked, and controlling means for supplying power to the auxiliary devices.

10. A power actuated system of switch control comprising: a switch, operating means for unlocking, moving and locking the switch, a power actuated auxiliary device for locking the switch when power is applied to unlock the switch, a power actuated auxiliary device controlled by the operating means for additionally locking the switch, unless previously unlocked, when power is applied to move the switch, and controlling means for supplying power to the operating means.

11. A power actuated system of switch control comprising: a switch, operating means for unlocking, moving and locking the switch, two auxiliary locking devices which when sequentially moved into locking position by power admit power a plurality of times to the operating means to effect the recited cycle of operations thereof, said auxiliary locking devices being controlled by the position of said operating means, whereby the position of the operating means is tested, and means for supplying power sequentially to the auxiliary locking devices.

12. A power actuated system of switch control comprising: a switch, operating means for unlocking, moving and locking the switch by stages, each stage being controlled by a separate act of the operator, power actuated auxiliary locking means which when moved into locking position admits power to the operating means to effect the recited cycle of operations thereof, said auxiliary locking means being controlled by the position of said operating means, whereby the position of the operating means is tested, and means for supplying power to the auxiliary locking means.

13. A power actuated system of switch control comprising: a switch, a motor element and connections for unlocking and locking the switch, a motor element and connections for moving the switch, controlling means for supplying power selectively to said motor elements in a certain sequence, and means for locking the switch when the operating means are improperly supplied with power.
14. A power actuated system of switch control comprising: a switch, a motor element and connections for unlocking and locking the switch, a motor element and connections for moving the switch, auxiliary locking means for locking the switch against action by one motor element which when in locking position supplies power to the other motor element, and controlling means for supplying power to said auxiliary locking means.
15. A power actuated system of switch control comprising: a switch, a motor element and connections for unlocking and locking the switch, a motor element and connections for moving the switch, auxiliary locking means for locking the switch against action by one motor element which when in locking position supplies power to the other motor element, controlling means for supplying power to said auxiliary locking means, and means operated by the motor element to which power is supplied for cutting off power between the controlling means and auxiliary locking means.
16. A power actuated system of switch control comprising: a switch, a motor element and connections for unlocking and locking the switch, a motor element and connections for moving the switch, controlling means for supplying power selectively to said motor elements in a certain sequence, means for locking the switch when the operating means are improperly supplied with power, and means operated by the motor element moved for cutting off power between itself and the controlling means.
17. A power actuated system of switch control comprising: a switch, operating means for unlocking, moving and locking the switch, auxiliary locking means for the switch, normally unlocked, but which when locked supplies power to the operating means, and controlling means for supplying power to lock the auxiliary locking means.
18. A power actuated system of switch control comprising: a switch, operating means for unlocking, moving and locking the switch, auxiliary locking means for the switch, normally unlocked, but which when locked supplies power to the operating means, controlling means for supplying power to lock the auxiliary locking means, and means actuated by the movement of the operating means for cutting off power from the controlling means to the auxiliary locking means.
19. A power actuated system of switch control comprising: a switch, means for unlocking and locking the switch, separately operated means for moving the switch, auxiliary locking means which when in its locking position supplies power to actuate one of said means and at the same time locks the other means, and controlling means for supplying power to the auxiliary locking means to move it into its locking position.
20. A power actuated system of switch control comprising: a switch, means for unlocking and locking the switch, separately operated means for moving the switch, auxiliary locking means which when in its locking position supplies power to actuate one of the aforesaid means and at the same time locks the other of said means, controlling means for supplying power to the auxiliary locking means to move it into its locking position, and means operated by the means to which power is supplied through the auxiliary locking means for cutting off power between the controlling means and auxiliary locking means.
21. A power actuated system of switch control comprising: a switch, means for unlocking and locking the switch, separately operated means for moving the switch, an auxiliary locking device for each of said means which when in its locking position with respect to one of said means supplies power to actuate the other of said means, and controlling means for selectively supplying power to the auxiliary locking devices to move them into locking position.
22. A power actuated system of switch control comprising: a switch, means for unlocking and locking the switch, separately operated means for moving the switch, an auxiliary locking device for each independent means which when in its locking position with respect to one of said means supplies power to actuate the other of said means, controlling means for selectively supplying power to the auxiliary locking devices to move them into locking position, and means operated by the means to which power is supplied through the auxiliary locking devices for cutting off power between the controlling means and auxiliary locking device.
23. A power actuated system of switch control comprising: a switch, power actuated operating means for unlocking, moving and locking the switch, auxiliary locking means which when in its locking position supplies power to a part of said operating means and locks another part of said operating means, and controlling means for supplying power to and locking said auxiliary locking means.
24. A power actuated system of switch

- control comprising: a switch, power actuated operating means for unlocking, moving and locking the switch, auxiliary locking means which when in its locking position supplies 5 power to a part of said operating means and locks another part of said operating means, controlling means for supplying power to and locking said auxiliary locking means, and means actuated by the part of 10 the operating means moved for cutting off power between the controlling means and the auxiliary locking means.
25. In a system of power actuated switch control, a switch, a lock-rod connected 15 thereto, a solenoid having two oppositely acting coils, a locking member for said lock-rod constituting the core for said solenoid, actuating means for the switch, means for supplying power to said actuating means, 20 and means connected to said locking member for controlling the supply of power to said actuating means.
26. In a system of power actuated switch control, a switch, a lock-rod connected 25 thereto, a solenoid having two oppositely acting coils, a locking member for said lock-rod constituting the core for said solenoid, actuating means for the switch, means for supplying power to said actuating means, 30 means connected to said locking member for controlling the supply of power to said actuating means, and an auxiliary locking device for said locking member actuated by the application of power to the actuating 35 means.
27. In a system of power actuated switch control, a switch, a lock-rod connected thereto, a locking member for said lock-rod, means for moving said locking member into 40 and out of locking position, electrically operated actuating means for moving the switch, means for supplying current to said actuating means, an auxiliary locking solenoid for said locking member actuated by 45 the application of current to the actuating means, and a controller connected to said locking member for controlling the supply of current to said actuating means.
28. In a system of power actuated switch control, a switch, a lock-rod connected 50 thereto, a solenoid having two oppositely acting coils, a locking member for said lock-rod constituting the core for said solenoid, actuating means for the switch, means for supplying power to said actuating means, means connected to said locking member for controlling the supply of power to said actuating means, an auxiliary locking device for said locking member actuated by 55 the application of power to the actuating means, and means connected to said auxiliary locking device for controlling the supply of power to the actuating means.
29. In a system of power actuated switch control, a switch, a lock-rod connected 60 thereto, a locking member for said lock-rod, means for moving said locking member into and out of locking position, electrically operated actuating means for moving the switch, means for supplying current to said actuating means, an auxiliary locking solenoid for said locking member actuated by 65 the application of current to the actuating means, and means connected to said auxiliary locking device for controlling the supply of power to the actuating means.
30. In a system of power actuated switch control, a switch, a throw-rod connected 70 thereto, a rotatable member for moving said throw-rod, means for unlocking and locking the switch, and an auxiliary locking device which supplies power to said locking means 75 and which prevents rotation of the rotatable member.
31. In a power actuated system of switch control, a movable member, power actuated means for moving said member in opposite 80 directions, controlling means for supplying power to said actuated means, and a controller actuated by the movable member which when at rest directs power supplied by the controlling means to move the member in one direction and which when initially moved in one direction by the movable member directs the power supplied by the controlling means in either of two ways whereby the controlling means may move 85 the said member in either direction.
32. In a power actuated system of switch control, a movable member, power actuated means for moving said member in opposite 90 directions, two power connections to said power actuated means one for each direction of movement of the movable member, controlling means for supplying power to either 95 of said connections, and a controller actuated by the movable member which when at rest directs power supplied by the controlling means to one of said connections to move the member in one direction and which when initially moved by the movable member directs the power supplied by the controlling means to either connection to move the member in the corresponding direction.
33. A power actuated system of switch control, comprising, a switch, operating means for unlocking, moving and locking 100 the switch, means for supplying power a plurality of times to said operating means to effect the movement thereof by stages, each stage being controlled by a separate act 105 of the operator, means for preventing any stage of movement unless the previous stage has been completed, and means for reversing the movement of the operating means during any stage of movement to restore the parts to their original position.

34. A power actuated system of switch control comprising, a switch, a motor element and means for unlocking and locking the switch, a motor element and means for moving the switch, auxiliary locking means for locking the switch if power is supplied to either motor element out of proper sequence, and power supply means to actuate the motor elements in a certain sequence 10 capable of reversal to supply power to reverse the movement of the locking or moving means of the motor elements during the travel of said means.
35. A power actuated system of switch control comprising a switch, operating means for unlocking, moving and locking the switch, means for supplying power a plurality of times to said operating means to effect the recited cycle of movements 15 thereof by stages in a certain sequence, each stage being controlled by a separate act of the operator, auxiliary locking means for locking the switch in case power is supplied to effect a stage of movement out of its sequence, said power supplying means being capable of reversal during any stage of movement to restore the parts to their original position.
36. In a power actuated system of switch control, a switch, a locking member controlling said switch, power actuated means for moving said locking member in opposite directions, controlling means for supplying power to said actuating means including a controller actuated by the locking member which when at rest directs the power supplied to move the locking member 20 25 30 35
- in one direction and which when initially moved in one direction by the locking member directs the power supplied in either of two ways whereby the controlling means may move the locking member in either direction.
37. In a power actuated system of switch control, a switch, power actuated means for moving said switch in opposite directions, controlling means for supplying power to said actuating means including a controller actuated by the power actuated means which when at rest directs the power supplied to move the switch in one direction and which when initially moved in one direction by the power actuated means directs the power supplied in either of two ways whereby the controlling means may move the power actuated means in either direction.
38. A power actuated system of switch control comprising: a tower machine, a source of current, a switch, a switch machine having operating means for unlocking, moving and locking the switch, conductors leading from the source of current through the tower machine to the switch machine, and means included in said switch machine whereby a cross in the conductors locks the switch.

Signed at Pittsburgh, in the county of Allegheny, and State of Pennsylvania, this 9th day of April A. D. 1914.
